CLAIM

The ornamental design for a utility wrench, as shown and described.

DESCRIPTION

FIG. 1 is a perspective view of the utility wrench of the invention shown with the side mounted screw driver blades in the retracted position;

FIG. 2 is a bottom view of the utility wrench of FIG. 1; FIG. 3 is a rear end view of the utility wrench of the invention, as viewed from the right end of FIG. 2;

FIG. 4 is a front end view of the utility wrench, as viewed from the left end of FIG. 2;

FIG. 5 is a bottom view of the utility wrench of the invention; FIG. 6 is a left side view of the utility wrench of FIG. 1; FIG. 7 is a right side view of the utility wrench of FIG. 1; and, FIG. 8 is a perspective view of the utility wrench of the invention, similar to FIG. 1, but with the side mounted screw driver blades in the extended position.

The broken lines shown on the utility wrench are included for the purpose of illustration only and form no part of the claimed design.
